UNITED STATES PATENT OFFICE

EDMUND J. STONE, OF NEW YORK, N. Y.

STREET SIGN AND TRAFFIC SIGNAL

Application filed April 12, 1928. Serial No. 269,499.

This invention relates to street sign and traffic signals as used at the intersection of highways or streets, one of its objects being to convey information of highly desirable nature to travellers as to the names of the streets at their corners, and also towards what points of the compass they extend. As is well known, strangers when reading street signs are not always able to determine which direction is east or west, or north or south, and in many cases this information is important, especially to drivers of motor cars.

It is also obvious that this device can be used to advantage in country or suburban districts where the points of the compass are frequently of the greatest importance.

A further feature is to combine with such street signs a series of colored lights acting as traffic signals, these lights appearing in a chamber adjacent the signs and also showing through the signs rendering the legends plainly visible during darkness.

Another aim is to provide means whereby the signs may be changed at will and the interior of the sign casings readily cleaned.

These important objects are accomplished by the novel design, construction and combination of parts as hereinafter described and shown in the annexed drawing forming a material part hereof and in which:—

Figure 1 is a front elevational view of a combined street sign and traffic signal as made in accordance with the invention.

Figure 2 is a longitudinal sectional view of the signal chamber, showing the parts therein and rear view of the sign, the cover being removed.

Figure 3 is a perspective view showing a preferred arrangement of the devices as attached to a support.

The pole or mast, designated by the numeral 5, is of the usual conventional type as employed in carrying street lights and obviously is hollow to accommodate conductors leading to the lamps used.

Secured at a suitable height on the pole 5 is an encircling clamp 6 having two or more tubular supports 7, arranged at right angles one with another and upturned at

their outer portions to rigidly engage the under sides of sign carrying casings 8.

Each of these casings presents a central oblong rectangular panel 9, having adjacent its ends triangular panels 10, the central panels bearing the name of the intersecting streets or avenues and the triangular panels carrying a letter representing the points of the compass to which they point.

The surfaces 11 and 12 above and below the main central panels are inclined inwardly towards the front, as are also the corresponding convergent surfaces 13—14 and 15—16 at the point and rear elements respectively, and preferably the points of the casings are arranged in close proximity to the pole 5.

The central panels are engaged by inreaching narrow flanges 17 and the end panels by corresponding flanges 18, permitting interchange of the panels which bear any desired inscription, preferably in dense black upon the panels which are transparent.

Rear cover plates are provided to complete the casings, these plates being attached by hinges 20, either at their top or bottom edges and held when in operative position by clips 21, and all of the casing elements are provided with ventilating perforations 22.

Secured to the blunt outer ends of the casings 8 by spot welding or like rigid means, are the convergent end members of rectangular sheet metal containers 23 having perforations 24 in their walls, and provided with removable outer end plates 25.

The front wall may support transparent panels 26 bearing inscriptions regarding the streets and fixed to the inner side of the plates 25 are blocks 27 in which are set three sockets 28, each containing a lamp 29, the colors being preferably red, white and green, in accordance with the traffic rules.

Set in the containers 23, at their junction with the casings 8, is a lens 30 by which light from any of the lamps 29 is transmitted to the interiors of the casings, and in order to increase the lighting effect, reflectors 31 are fixed in the containers in such manner as to concentrate and direct the light from the lamps through the lens into the casings 8, causing it to show through the transparent

panels so that the legends are plainly visible.

It will be understood that current passing through the poles 5 is branched to extend through the clamp 6, and supports 7 to the 5 socket blocks 27 and that the lamps are operated by the same circuit that conveys current to the street lights and changed in accordance therewith.

10 Although the foregoing is descriptive of the preferred embodiment of the invention, it will be apparent that minor changes may be made in its construction, without the exercise of invention or conflicting with the 15 scope of the claims hereto appended.

Having thus described the invention, what is claimed as new and desired to secure by Letters Patent, is:—

1. A street intersecting sign comprising 20 a pair of casings extending in the direction of the intersecting streets, panels in the fronts of said casings to show respectively the name of the streets and direction in which the streets extend, said panels being removable 25 engaged, cover plates hinged at the rear of said casings, lamp containers communicating with remote ends of said casing, a series of differently colored lamps in each container to show through the casing panels, 30 and transparent panels in the front walls of said containers bearing legends relating to the streets.

2. The combination with a street light pole, 35 of a pair of street sign casings having transparent panels bearing the names of intersecting streets and the direction in which the streets extend, lamp containers at the remote ends of said casings, a series of vari-colored lamps therein, and lenses at the junctions of said containers and casings whereby the latter may be illuminated when any 40 of the lamps are in operation.

3. The combination with a street light pole, 45 of a pair of street sign casings having transparent panels bearing the names of intersecting streets and the direction in which the streets extend, said casings having sharp and blunt ends, the sharp ends being contiguous to the pole, containers attached to 50 the blunt ends of said casings, a series of differently colored lamps in said containers, reflectors in said containers to direct light into the casings, and lenses to receive light prior to entering the casings.

55 4. The combination with a street light pole, of a pair of street sign casings having transparent panels bearing the names of intersecting streets and the direction in which the streets extend, said casings having sharp and 60 blunt ends, the sharp ends being contiguous to the pole, the walls of said casings being perforate, cover plates hingedly engaged at the rear of said casing, means for detachably engaging the panels to the front walls of said 65 casings from the inner sides thereof, con-

tainers communicatively attached to the blunt ends of the casings, lens interposed at the joints therebetween, a series of lamps respectively red, white and green carried in said containers, and a reflector common to all 70 of said lamps to direct light rays through said lens into the casings.

In testimony whereof I have hereunto affixed my signature.
